IMPLEMENT FOR DRAWING TRACK RAILS
TO GAUGE

William E. Brown, Pittsburgh, Pa.

Application April 6, 1933, Serial No. 664,702

9 Claims. (Cl. 254—44)

This invention relates to devices useful in railroad construction and maintenance to draw track rails to gauge.

Considered from the broadest aspect, my invention is directed toward the provision of a simple and inexpensive track manipulating implement which is light but sturdy in construction; which is capable of very easy actuation so that one workman alone can move track rails into exact gauge relation with a minimum expenditure of manual effort and without necessitating the use of a gauge spacing bar such as is ordinarily required in this operation; and which, moreover, is collapsible into compact form for convenience of ready carriage from place to place as needed.

In connection with a track manipulating implement having the mentioned attributes, it is an aim of my invention to provide releasable locking means, whereby, as the implement is contracted to draw one rail toward the other, its parts are automatically secured against relative movement to prevent spreading of the rails subsequently during spiking.

Another object of my invention is to provide facilities whereby a manipulating device of the kind referred to can be adapted for use with rails having base flanges of different widths.

Still another object of my invention is to make provisions whereby an implement of the specified sort may be adapted for use in track circuited territories.

Still other objects and attendant advantages of this invention will be manifest from the detailed description following of the attached drawing, wherein Fig. I is a transverse sectional view of a railroad track with my improved implement positioned in readiness for operation to draw one of the track rails into proper gauge relation with the other.

40 Fig. II is a view similar to Fig. I showing the implement after the performance of the track drawing operation.

Fig. III is a perspective view of the implement drawn to a somewhat larger scale.

45 Fig. IV is a detail sectional view taken as indicated by the arrows IV—IV in Fig. III.

Fig. V is a fragmentary vertical longitudinal sectional view of the implement showing the locking means.

50 Fig. VI is a perspective view of a substitute part whereby the implement may be adapted for use in track circuited territories; and

Fig. VII is a perspective view showing the implement collapsed.

55 As herein delineated, my improved track rail

manipulating implement comprises a pair of aligned bar members 10, 11 having hooks 12, 13 at their outer ends, one to underreach the track rail R and to engage the outer edge of its flanged base B, and the other to underreach the rail R' and to engage the outer edge of its flanged base B'. The inner ends of the bar members 10, 11 fit the clevis 14 (see Figs. III and IV) of an actuating toggle member 15 and pivot on the smooth-surfaced medial shank portions of fulcrum screw bolts 16, 17 extending crosswise of the clevis. Also fitting the clevis 14 of the toggle member 15 is a gravity influenced detent 18 which is pivoted to rock on another fulcrum screw bolt 19 extending crosswise of the clevis above the screw bolt 16, 60 for capacity to cooperate with teeth 20 along the top edge of the bar member 10. As shown, the detent 18 has a rearward treadle projection 21 so that it may be released from the teeth 20 when required, by pressure of the foot on said treadle. 75 Projecting laterally from one side of the toggle member 15 is a pair of spaced eyes 22, 23 for insertion of a crow bar or the like indicated at 24 to serve as an operating handle for the implement.

In use, the implement is arranged as shown in Fig. I with the hook 12 engaging the outer edge of the flange base B of the fixed rail R as already explained, and with the bar member 11 extended relative to the bar member 10 and its hook 13 engaging the outer edge of the flange base B' of the rail R' also as already explained. The bar 24 is thereupon swung toward the right from the position of Fig. I, to that shown in Fig. II, whereby, through the action of the toggle member 15, the implement is contracted until the top edge of the bar member 11 contacts with the bottom edge of the bar member 10 as shown in Figs. II and V. As a consequence, the rail R' is moved toward the rail R a predetermined distance to bring it into exact gauge relation with the latter. During the described swing of the handle 24, the locking detent 18 rides idly over the teeth 20 on the bar member 10 until it finally locks with the last of said teeth as shown in Figs. II and V. As a result the component parts of the implement are automatically locked in the positions shown in Fig. II to hold the rail R' against spreading while spikes are driven into the ties T to secure it. In this connection, it is to be particularly noted that upon removal of the handle 24 in Fig. II, the implement is devoid of any projections which would preclude passage of trains over the track.

After the rail R' is secured with spikes, the 110

implement is removed simply by pressing the treadle 21 of the locking detent 18 to withdraw the latter from the teeth 20 on the bar member 10, and by swinging the operating bar 24 back to the position of Fig. I to effect release of the hooks 5 12, 13 from the rails.

In order that the implement may be used in placing track rails having base flanges of different widths, the hook 13 is made as a separate piece as shown, and provided in its shank portion with a number of suitably-spaced staggeringly-arranged holes 25 for selective engagement by a depending stud projection 26 on the bar member 11.

In Fig. VI, I have shown a supplemental hook member 13a having a liner 27 of insulating material associated therewith to prevent the possibility of short circuiting between the rails R, R' when the implement is used in track circuited territory.

For the sake of lightness I prefer to construct the component parts of the implement as forgings from wrought metal. Thus after being collapsed as shown in Fig. VII by swinging the bar member 11 about the pivotal connection 17 with the toggle member 15 into parallel relation with the bar member 10, the implement can be conveniently carried about from place to place.

Having thus described my invention, I claim:

1. An implement for drawing track rails to gauge comprising a pair of aligned bar members with end hooks to transversely underreach the track rails and engage the outer edges of their flanged bases, a toggle member connecting the inner ends of the two bar members, provisions 30 on the toggle member enabling the use of a crow bar or the like as an actuating handle, and an automatically-operative releasable locking means for securing the parts against relative movement after contraction of the implement to prevent spreading of the track rails during spiking.

2. An implement for drawing track rails to gauge comprising a pair of aligned bar members with end hooks to transversely underreach the track rails and engage the outer edges of their flanged bases, a toggle member connecting the inner ends of the two bar members, said toggle member having a pair of spaced laterally projecting eyes for insertion of a crow bar or the like 45 as an actuating member, and an automatically operable releasable locking means for securing the parts against relative movement after contraction of the implement to prevent spreading of the rails during spiking.

3. An implement for drawing track rails to gauge comprising a pair of aligned bar members with end hooks to transversely underreach the track rails and engage the outer edges of their flanged bases, a toggle member connecting the inner ends of the two bar members, an actuating 55 handle for the toggle member, and an automatically-operative releasable gravity detent fulcrumed on the toggle member and engaging teeth on one of the bar members thereby to secure the parts against relative movement after contraction of the implement to prevent spreading of the track rails during spiking.

4. An implement for drawing track rails to gauge comprising a pair of aligned bar members with end hooks to transversely underreach the track 70 rails and engage the outer edges of their flanged bases, a toggle member with its ends pivotally connected respectively to the inner ends of two bar members, a handle whereby the toggle member may be actuated to contract the implement,

and an automatically-operative gravity detent fulcrumed on the toggle member and engaging ratchet teeth on one of the bar sections to secure the parts against relative movement after contraction of the implement to prevent shifting of the track rails during spiking, said detent having a rearward treadle projection for foot pressure release.

5. An implement for drawing track rails to gauge comprising a pair of aligned bar members with end hooks to engage the outer edges of the rails, a toggle member with a clevis to pivotally receive the inner ends of the bar members, a removable handle whereby the toggle member may be actuated to contract the implement, and a gravity detent also engaged pivotally within the clevis of the toggle member and adapted to cooperate with teeth on one of the bar members in automatically locking the parts against relative movement upon contraction of the implement to prevent spreading of the rails during spiking.

6. An adaptable implement for drawing track rails with base flanges of different widths to gauge, comprising a pair of aligned bar members, one with an integrally formed hook end to underreach one track rail and to engage the outer edge of its flange base, and the other bar member having a perpendicular stud projection selectively engageable with a series of apertures in a separate end hook member for underreaching the other track rail and engaging the outer edge of its flange base, said apertures being longitudinally spaced to accord with the base width variations of the different rails, a toggle member connecting the inner ends of the hook bar sections, a handle for actuating the toggle member to contract the implement, and a conformative removable liner of insulating material fitting into the separate hook member aforesaid to enable the use of the implement in track-circuited territory.

7. An implement for drawing track rails to gauge comprising a pair of aligned bar members with end hooks to transversely underreach the track rail and to engage the outer edges of their flanged bases, a toggle member with an upwardly-extending actuating handle connecting the inner ends of the bar members, said actuating handle being removable to permit passage of trains over the sections of the track rails held by the implement, and automatically operable means for securing the parts against relative movement upon contraction of the implement.

8. An adaptable implement for drawing track rails with base flanges of different width to gauge comprising a pair of aligned bar members, one with an integrally formed hook end to underreach one track rail and to engage the outer edge of its flanged base, and another bar member having a perpendicular stud projection selectively engageable with a series of apertures in a separate end hook member for underreaching the other track rail and engaging the outer edge of its base flange, said apertures being longitudinally spaced to accord with the width variations of the different rail base flanges, a toggle member connecting the inner ends of the hook bar sections, and a handle for actuating the toggle member to contract the implement.

9. An adaptable implement for drawing track rails with base flanges of different widths to gauge comprising a pair of aligned bar members, one with an integrally formed hook end to underreach one track rail and to engage the outer edge of its flange base, and the other bar

member having a perpendicular stud projection selectively engageable with a series of apertures in a separate end hook member for underreaching the other track rail and engaging the outer edge of its flange base, said apertures being longitudinally spaced to accord with the variations in the base flange widths of the different rails, a swingable clevised handle-actuated toggle mem-

ber with spaced pivots for connection of the bar members, said toggle member being limited in its swing through overlap and contact of the pivoted ends of the bar members in superposed relation with determination of a definite degree of contraction for the implement and consequent drawing of the different track rails to exact gauge.
